RESPIRATOR

Leslie H. M. Bickel, Chula Vista, Calif.

Application August 24, 1953, Serial No. 26,562

Term of patent 14 years

(Cl. D83—1)

To all whom it may concern:

Be it known that I, Leslie H. M. Bickel, a citizen of the United States, residing at Chula Vista, in the county of San Diego and State of California, have invented a new, original, and ornamental Design for a Respirator, of which the following is a specification, reference being had to the accompanying drawing, forming a part thereof, and wherein:

Figure 1 is a front elevation view of a respirator showing my new design;

Figure 2 is a rear elevation view thereof;

Figure 3 is a top plan view thereof;

Figure 4 is a bottom plan view of my new design;

Figure 5 is a sectional view of my new design taken on the line 5—5 of Figure 1; and

Figure 6 is a side elevation view of my design for a respirator.

The side not shown in the drawing is the same as the side shown in Figure 6.

I claim:

The ornamental design for a respirator, as shown and described.

LESLIE H. M. BICKEL.
